PACKAGE DISPENSING DEVICE

Leo Lichtenstein, Chicago, Ill.

Application August 3, 1937, Serial No. 157,145

1 Claim. (Cl. 312—42)

The device of the present invention is designed as a combined package dispenser and advertising display board or panel; and the object of the present invention is to simplify and cheapen the construction to such a degree that if desired the device may be used for a single service and thereafter discarded, although the dispenser is adapted to be refilled without difficulty for additional service.

10 The device is intended primarily for the dispensing of packages containing razor blades, confections, or other small objects, and also to afford adequate space for the advertising of such articles in an attractive and conspicuous manner.

15 Further objects and details will appear from the description of the invention in conjunction with the accompanying drawing, wherein,

Figure 1 is a perspective view of the device as a whole;

20 Fig. 2 is a perspective view showing the rear or open side of one of the dispenser chutes, with the packages arranged in column form;

Fig. 3 is a sectional elevation taken on line 3—3 of Fig. 1;

25 Fig. 4 is a cross sectional view taken on line 4—4 of Fig. 1; and

Fig. 5 is a view of the metallic blank from which the dispenser chute is formed.

As shown, the device consists of a backing panel 10 of suitable size and shape to display advertising matter relating to the articles being dispensed, which backing panel in the present instance serves as a mounting for two dispenser chutes 11 of identical formation, which are preferably located in spaced relation to permit the lower center of the panel to be employed for advertising purposes.

Each of the dispenser chutes is formed from a blank of thin metal comprising a front centrally disposed body portion 12, having formed therein a vertically elongated slot or opening 13 and having along each side edge a rectangular wing 14 adapted to be bent along a folding line 15 to afford the side wall of the dispenser. The body portion 12 of the blank at its lower edge is provided with a lower tongue 16, and at its upper edge with a similar upper tongue 17 adapted to be struck inwardly along folding lines 18 and 19 respectively, to afford the bottom and top walls 50 of the dispenser.

Near the lower edge of the blank is formed a transversely elongated finger slot 20 which extends through the body of the blank and into the wings 14, so that when the wings are bent into right angular relation to the body, the slot thus

afforded will extend across the entire front of the dispenser near its bottom and back into each of the side walls to afford a convenient slot for the removal of one of the lowermost packages 21 of a column of rectangular packages contained 5 within the dispenser.

In order to prevent accidental displacement, a light flat spring tongue 22 is provided which normally stands in vertical relation across the slot 20, which spring tongue at its lower end is 10 provided with an inwardly extending finger 23 secured by a rivet 24 to the bottom of the dispenser. The arrangement is one which, in the present instance, normally presents the second lowermost package to the center of the slot in 15 such a way that it may be drawn out by the user, thereby causing the spring tongue to yield and permit removal of the package.

The dispenser is secured to the backing panel by four tongues 25, properly spaced to pass 20 through slots 26 in the backing panel and to be thereafter struck inwardly to overlie the rear face of the panel, thereby holding the dispenser in fixed relation thereon.

In order to rapidly fill the dispenser chute, it 25 is left open at the rear so that an entire column 25 of packages may be inserted as a unit rather than separately, and in order to temporarily hold the column in place while the dispenser chute is being mounted upon and secured to the panel, the upper 30 tongue 17 is adapted to be bent inwardly into oblique relation to the front wall of the dispenser and between the side walls thereof, as shown in Fig. 3, so as to exert sufficient pressure upon the packages to temporarily prevent displacement 35 and until the tongues 25 can be entered through the slots 26 in the backing panel and secured thereto. After being thus secured, the backing panel will itself provide the rear wall for each of the dispenser chutes mounted thereon and hold 40 the dispenser rigidly so that the packages may be removed one at a time from the lower portion of the column as occasion may require.

The device as a whole affords an attractive 45 display for the packages, which are visible through the front slot 13, and permits a much greater number of packages to be mounted upon an advertising display panel than cou'd be carried if the packages were secured flatwise thereon, 50 or in other than column form.

The device is especially useful in hotel rooms, or in public places where it is desired to dispense razor blades, advertising novelties or the like, and is peculiarly adapted for use where such 55

novelties are dispensed freely for advertising purposes.

I claim:

5 In a dispensing device, the combination of a
backing panel adapted to display advertising
matter, and a dispenser chute mounted thereon
and adapted to contain a column of packages, the
dispenser chute comprising a front wall, top and
bottom walls and side walls, and being provided
10 near the base with a dispensing slot to permit
removal of the packages one at a time, the rear
of the dispenser chute being open to permit the

insertion of a column of packages, and attaching
means for securing the dispenser chute to the
backing panel after being filled with packages,
the backing panel after attachment affording a
rear closing wall for the chute, the top wall of the 5
dispenser chute extending inwardly and down-
wardly at an acute angle between the side walls
to exert temporary pressure upon the column of
packages to prevent displacement thereof before
attachment of the dispenser chute to the backing 10
panel.

LEO LICHTENSTEIN.
